(57) **CLAIM**

The ornamental design for an electrical power unit for a work surface, as shown and described.

DESCRIPTION

FIG. 1 is a top perspective view of a first embodiment of an electrical power unit for a work surface, showing our new design;

FIG. 2 is a bottom perspective view of the electrical power unit for a work surface of FIG. 1;

FIG. 3 is a top plan view of the electrical power unit for a work surface of FIG. 1;

FIG. 4 is a bottom plan view of the electrical power unit for a work surface center of FIG. 1;

FIG. 5 is a front elevation of the electrical power unit for a work surface of FIG. 1;

FIG. 6 is a rear elevation of the electrical power unit for a work surface of FIG. 1;

FIG. 7 is a left side elevation of the electrical power unit for a work surface of FIG. 1;

FIG. 8 is a right side elevation of the electrical power unit for a work surface of FIG. 1;

FIG. 9 is a top perspective view of a second embodiment of an electrical power unit for a work surface, showing our new design;

FIG. 10 is a bottom perspective view of the electrical power unit for a work surface of FIG. 9;

FIG. 11 is a top plan view of the electrical power unit for a work surface of FIG. 9;

FIG. 12 is a bottom plan view of the electrical power unit for a work surface center of FIG. 9;

FIG. 13 is a front elevation of the electrical power unit for a work surface of FIG. 9;

FIG. 14 is a rear elevation of the electrical power unit for a work surface of FIG. 9;

FIG. 15 is a left side elevation of the electrical power unit for a work surface of FIG. 9; and,

FIG. 16 is a right side elevation of the electrical power unit for a work surface of FIG. 9.
